UNITED STATES PATENT OFFICE.

CLARENCE E. ANDERSON, OF PECATONICA, ILLINOIS.

EXPLOSIVE-ENGINE-CONTROLLING MECHANISM.

1,223,844.

Specification of Letters Patent. Patented Apr. 24, 1917.

Application filed March 24, 1916. Serial No. 36,409.

To all whom it may concern:

Be it known that I, CLARENCE E. ANDERSON, a citizen of the United States, residing at Pecatonica, in the county of Winnebago and State of Illinois, have invented certain new and useful Improvements in Explosive-Engine-Controlling Mechanism; and I do hereby declare the following to be a full, clear, and exact description of the invention, such as will enable others skilled in the art to which it appertains to make and use the same.

This invention has for its object to provide an improved and efficient float-operated mechanism designed for use in connection with a water tank and explosive engine by which the water is pumped into the tank for breaking the ignition circuit, cutting off the throttle valve and stopping the flow of lubricating oil to the engine when the water reaches a predetermined level.

With this and other objects in view, the invention consists in the novel construction, combination, and arrangement of parts as will be hereinafter specifically described, claimed and illustrated in the accompanying drawing, in which:

Figure 1 represents a side elevation of the float-operated mechanism, illustrating the same operatively connected with an explosive engine and a water tank, and

Fig. 2 represents an end elevation of the float released and spring actuated part, removed from the remainder of the controlling mechanism.

Referring to the drawing in detail, wherein similar reference numerals designate corresponding parts throughout the several views, the numeral 5 indicates an ordinary type of water tank, which is adapted to be filled with water conducted by a pipe 5^a from a pump 5^b. The pump 5^b is connected by a belt or other power transmitting device 6^a with an explosive engine 6, including the usual inlet pipe 7, throttle valve operating hand wheel 8 and switch arm 9 movable over a relatively stationary contact 10 for closing the electric ignition circuit to the spark plug 11 secured in the cylinder wall of the engine. A lubricating oil reservoir 12 is supported by a pipe 13 by which the lubricant is conducted to the working parts of the engine 6, and the passage of the lubricating oil from the reservoir 12 to the feed pipe 13 is controlled by a suitable type of valve 14, carrying a stem 15. A lever 16 is pivotally

secured to the upper exposed end of the stem 15 and is adapted, when moved into vertical position to engage the top of the reservoir 12 and retain the valve 14 in open position. 60 However, when the lever is swung to horizontal position illustrated in dotted lines in Fig. 1, the side of said lever is engaged with the top of the reservoir 12 and the valve 14 is permitted to move to closed position, and thereby stop the flow of oil from the reservoir 12 to the feed pipe 13. 65

A lever 17 is pivotally secured at 18 to the top edge of the tank 5 and is provided at its inner end with a float 19, which floats upon the surface of the water contained in the tank 5. The opposite end of the lever 17 is connected by a flexible member 20 with the relatively long arm of a bell crank 21, which is pivotally secured at 22 to a post or upright 23. One arm of the bell crank 21 is connected by a chain 24 with the post 23, whereby the upward movement of the relatively long arm is limited. The relatively short and vertically disposed arm of the bell 70 crank 21 is connected with a flexible member 25 to which is attached a link 26, having connection at its opposite end with a contractile spring 27. The end of the spring 27 opposite the link 26 is connected with a second 75 link 28, which is attached to a wall or other suitable support 29 by a hook 30 and flexible member 31.

A relatively long link or brace 32 is connected at one end with the link 28 and at 80 the opposite end with the bight portion of a bell crank 33, one arm of which is pivotally connected with the intermediate link 26, and the opposite end thereof is connected with a depending flexible member 34. 85

A plate 35 is secured in relatively close relation to the explosive engine 6 and pivotally supports a latch plate 36, having an offset end 37 for engaging and locking a spring actuated member 38 in vertical position. 100 The member 38 is preferably constructed of a single piece of wire bent centrally to form an inverted U-shaped portion 39, having angular ends 40 pivotally secured to the plate 35 by bearing members 41 and connected with angularly directed arms 42, having looped terminals 43. The parallel portions of the U-shaped portion 39 are connected with a clip 44 to which is attached one end of a contractile spring 45. The opposite end 105 of the spring 45 is secured at 46 to the base plate 35 and the tension thereof normally

tends to swing the pivoted spring actuated member 38 in a direction away from the explosive engine 6.

Flexible members 47 and 48 are connected 5 with the looped end 43 of one of the arms 42, the opposite end of the flexible member 47 being connected with an arm 50 carried by the throttle operating wheel 8 and the flexible member 48 being connected with the 10 free end of the switch arm 9. The looped terminal 43 of the other arm 42 is connected by a flexible member 51 with the free end of the valve controlling lever 16.

When the supply of water in the tank 5 runs low and it is desired to fill it, the plate 36 is engaged with the pivoted member 38, so as to lock the latter in vertical position against the tension of the spring 45 in the position illustrated in full lines in Fig. 1.

20 The switch arm 9 is subsequently swung so as to engage the contact 10, the lever 16 swung to vertical position so as to partially open the valve 14 and permit an adequate supply of oil to flow to the working parts 25 of the engine, and finally the throttle valve adjusting wheel 8 is properly adjusted and the engine set in operation. As the level of the water rises within the tank 5, the end of the lever 17 carrying the float 19 is elevated 30 and when the water level reaches a predetermined height the progress of the movement of the several parts of the controlling mechanism is such as to cause the bell crank 33 to swing against the tension of the spring 35 27, draw the flexible member 34 upwardly, together with the free end of the plate 36, and release the pivoted member 38. When released, the pivoted member 38 is swung outwardly of the engine 6 under the influence 40 of the spring 45, imparting a longitudinal pull in the direction of movement of the pivoted member to the several flexible members 47, 48 and 51, thereby moving the switch arm 9 off of the contact 10 and breaking 45 the electrical circuit of the engine, swinging the arm 50 so as to close the throttle valve controlled by the wheel 8 and moving the lever 16 to the horizontal and dotted line position illustrated in Fig. 1, so as to

permit the oil valve 14 to close, and thereby 50 stop the feed of oil to the engine while the latter is in an inoperative condition.

What I claim is:

What I claim is,
1. In combination, an explosive engine, a pump connected therewith, a tank connected with the pump, and a float arranged in the tank, a base plate, an inverted U-shaped member pivotally secured to said base plate, arms carried by the U-shaped member, engine-controlling means, flexible operating members carried by the arms and connected with the engine controlling means, spring means normally tending to move said U-shaped member in one direction, a pivoted latch plate having an offset adapted to lock said pivoted member in adjusted position, and means operable by the float to release said latch plate. 55 60 65 70 75 80 85 90 95

2. In combination, an explosive engine, a pump connected therewith, and a tank connected with the pump, a pivoted lever, a float carried by one end of said lever and extending into the tank and operable by the liquid therein, a support, a spring connected with said support, a link connected with said spring, a connection between said link and said lever including a pivoted bell crank, a relatively long link connected with the end of said spring opposite the first-mentioned link, a bell crank pivotally connected at its right portion to the relatively long link and having one end connected with the first-mentioned link, a base plate, a member pivotally secured to said base plate, engine controlling means operable by the pivoted member, spring means normally tending to move said pivoted member, a latch plate for locking said pivoted member in adjusted position, and means connecting the other arm of said second-mentioned bell crank with said latch plate. 70 75 80 85 90

In testimony whereof I affix my signature
in presence of two witnesses.

CLARENCE E. ANDERSON.
